UNITED STATES PATENT OFFICE.

STEPHEN M. MATHEWS, OF TORONTO, CANADA.

ELECTRIC-ALARM TRY-COCK.

SPECIFICATION forming part of Letters Patent No. 642,913, dated February 6, 1900.

Application filed April 14, 1899. Serial No. 713,071. (No model.)

To all whom it may concern:

Be it known that I, STEPHEN M. MATHEWS, a subject of the Queen of Great Britain, residing in the city of Toronto, in the county of 5 York, and Province of Ontario, Canada, have invented certain new and useful Improvements in Electric-Alarm Try-Cocks; and I hereby declare that the following is a full, clear, and exact description of the same.

This invention relates to certain new and useful improvements in electric alarms for steam-generating boilers, and it relates more particularly to its peculiar construction and arrangement and its relative position to the 15 water-line of the boiler, the object of the invention being to so arrange the apparatus that it will instantaneously sound an alarm when the water in the boiler has fallen below a predetermined level; and the invention consists, essentially, of providing the try-cock with an expansion-chamber in communication with either the water-column of the boiler or with the boiler itself, a hermetically-sealed air-chamber contiguous to the expansion- 20 chamber, a diaphragm actuated by the air within the hermetically-sealed air-chamber, and an adjustable contact-screw in circuit with the battery and alarm, through which the circuit is completed when the air in the 25 hermetically-sealed chamber is expanded to move the diaphragm into contact with the point of the contact-screw, as hereinafter more fully set forth, and more particularly pointed out in the claims.

In the drawings, Figure 1 is a sectional view of the apparatus. Fig. 2 is an enlarged sectional view of the upper part of the apparatus, showing the air-chamber, diaphragm, and contact-screw. Fig. 3 is a plan view of 35 the top of the same.

A represents the shell of the apparatus, one end of which is provided with an integrally-formed concavo-convex end *a* and the other end of which is provided with a screw-threaded 40 stem *a'* to be fitted into the boiler or water-column.

B represents a chamber within the shell A, and *b* represents an opening through the stem *a'*, communicating with the chamber B.

O represents the drain-cock, communicating with the chamber B contiguous to the inner side of the end *a*. The stem *a'*, when the

apparatus is in position, is fitted into the water-column or boiler and the water or steam passes from the boiler or water-column 55 through the opening *b* of the stem *a'* into the chamber B. By means of the drain-cock O the contents of the chamber B can be permitted to escape by opening its valve.

The end of the shell A is provided with a 60 dome S, between which and the concaved end of the shell is formed an air-chamber. Located centrally between the dome and the concaved end of the shell is a diaphragm D, the side face of which is opposed to the concaved end *a*, and which is made of electrically-conducting metal.

H represents a post provided with a screw-threaded stem *h*, fitted through the top of the dome S, and interposed between the screw-threaded stem *h* and the dome S is an insulated washer G to prevent electrical contact between the post and the dome. Passing through the post H is an adjustable contact-screw J, provided with a lock-nut I, adapted 75 to bear against the top of the binding-post, the lower end of which is adapted to be engaged by the diaphragm D when actuated by the expansion of the air in the chamber C, formed between the diaphragm and the concaved end of the shell.

M represents an opening from the chamber T between the diaphragm D and dome to allow of the exit of the air from the chamber when the diaphragm is actuated. 85

Formed through the shell A into the chamber C is an opening fitted with a screw N, by means of which the air can be admitted to the chamber. In order to provide a means of access to the chamber T and diaphragm through 90 the dome, the dome is provided with an enlarged opening fitted with a nut R, the shank of which is screwed into the opening, which is provided with a central bore to receive the insulated washer G, through which passes the 95 stem of the post H, the inner end of the post being locked to the washer by means of a nut, and the outer part of which is provided with a shoulder resting against the outer part of the washer. The post H is provided with an 100 extension L to receive the circuit-wire, and the extension L is provided with a set-screw for locking the wire to the extension L of the post H.

The use of the invention is as follows: The stem a' of the shell A is screwed into the boiler or water-column slightly below the water-line. When the water in the boiler or water-column 5 is at its normal level—that is, at the level of the water-line—it will pass through the opening b in the stem a' to the chamber B and prevents the passage of the steam from the boiler to the chamber. The contact-screw is ad-10 justed so that it will not engage the diaphragm until the temperature in the chamber B has risen above 212° Fahrenheit, which is the sensible temperature of boiling water. When the water in the boiler or water-column has 15 fallen below the water-line, the water will drain from the chamber B back into the boiler or water-column and allow of the passage of the steam from the boiler or water-column into the chamber B, and as the steam is al-20 ways under pressure in a generating-boiler it will increase the temperature of the chamber above 212° , raising the temperature of the air in the closed chamber C to the same point and cause the movement of the diaphragm 25 toward the point of the contact-screw, ground-30 ing the current by means of the contact-screw and the remaining parts of the apparatus, completing the circuit of the current through the wire F to the electric bell in any ordinary manner.

Having thus fully described my invention, what I claim as new, and desire to secure by Letters Patent, is—

1. An electric-alarm try-cock consisting of 35 an expansion-chamber communicating with the water-column or boiler, a concavo-convex

end for the expansion-chamber, a diaphragm opposed to the concavo-convex end, adapted to form between itself and the said end of the chamber a hermetically-sealed air-chamber, 40 a supplemental end for the expansion-chamber inclosing the diaphragm, an insulated post passing through the supplemental end, a contact-screw passing through the post, the point of which is adapted to be engaged by 45 the diaphragm when actuated by the expansion of the air within the hermetically-sealed air-chamber to complete the circuit to the alarm, substantially as specified.

2. An electric-alarm try-cock consisting of 50 an expansion-chamber communicating with the water-column or boiler, a concavo-convex end for the expansion-chamber, a dia-55 phragm opposed to the concavo-convex end, adapted to form between itself and the said end of the chamber a hermetically-sealed air-chamber, a supplemental end for the expansion-chamber inclosing the diaphragm, an in-60 sulated post passing through the supplemental end, a contact-screw in circuit with the alarm passing through the post, the point of which is adapted to be engaged by the dia-65 phragm when actuated by the expansion of the air within the hermetically-sealed air-chamber, which is provided with an opening between the diaphragm and supplemental end to allow of the escape of the air from within it, substantially as specified.

STEPHEN M. MATHEWS.
